Standard Electric Corporation, New York, N. Y.,
a corporation of Delaware

Application April 29, 1949, Serial No. 90,326

3 Claims. (Cl. 315—250)

1

This invention relates to circuit arrangements for using gas-filled cold cathode electric discharge tubes and is a continuation in part of the application of E. M. S. McWhirter, R. H. Dunn and P. W. Lennox, Serial No. 744,009, filed April 25, 1947.

In order to render such a tube conducting the gap between the control electrode and the cathode must be ionised and a positive potential must be applied to the anode with respect to the cathode. Taking a particular well known construction as an example, so long as the anode potential is 130 volts or more, the minimum ionisation current produced by a voltage of about 70 volts between control electrode and cathode is sufficient to cause current to flow between anode and cathode.

It is well known to connect such tubes in a chain. The cathode of each tube is connected to ground over a resistance having a condenser in parallel therewith and a point on this resistance is connected to the control electrode of the next tube, the values being so chosen that when one tube is conducting a potential of about 35 volts is impressed between the control electrode and cathode of the succeeding tube.

This is insufficient to ionise the gap between the two electrodes. Impulses are applied between the control electrodes and ground of all the tubes of such polarity as to impress an additional potential of about 35 volts with respect to ground on the control electrodes of all tubes simultaneously. This potential, added to the potential impressed on a control electrode from the preceding tube that is conducting is sufficient to ionise the gap between the control electrode and cathode.

The problem sometimes arises of impressing a desired potential, such as the priming potential of 35 volts mentioned above, on the control electrode of a principal tube only when two or more other tubes, referred to as additional tubes, are conducting at the same time.

The present invention provides a circuit arrangement in which gas-filled cold cathode tubes are employed, each tube having at least a control electrode and a cathode and in which said tubes are so connected that a desired biasing potential will only be applied to the control electrode of a principal tube when a predetermined number of similar additional tubes have been brought into conducting condition, said additional tubes being rendered conducting in any desired order, comprising a principal tube, a plurality of similar additional tubes, the cathode of each of said additional tubes being individually connected to ground through a circuit having a low resistance, a connection between a point on each of said low resistance circuits and the control electrode of said principal

2

tube over respective rectifiers, the values of said low resistance, the characteristics of said rectifiers and the direction in which they are connected in the circuit, and the potentials applied to the several electrodes of all said tubes being so selected that only a relatively small potential is applied to the control electrode of said principal tube until all said additional tubes have been rendered conducting, whereupon said desired biasing potential is impressed on said control grid.

The invention will be better understood from the following description taken in conjunction with the accompanying drawings in which—

Fig. 1 represents an embodiment of the invention employing only three tubes;

Fig. 2 is a diagram showing as an equivalent circuit the essential features of Fig. 1;

Fig. 3 is a diagram showing a more generalised form of the circuit of Fig. 2; and

Fig. 4 represents an embodiment of the invention employing six tubes.

Referring to the Fig. 1, there are shown three tubes 1, 2 and 3 of the same kind. Each tube is a three electrode gas filled tube having a cold cathode, a control electrode and an anode. The control electrode is represented as an arrow head and the cathode as a small circle, the cathode being the right hand electrode of the pair in the case of all three tubes. The anode of each tube is assumed to be connected to a positive source of 130 volts. When any tube, e. g. 1 becomes conducting the voltage drop across the anode cathode circuit of the tube is about 70 volts, and the potential across resistances 4 and 5 arises, after a short interval due to the charging of the condenser connected thereacross to a value of about 60 volts. The junction point between resistances 4 and 5 is connected to ground not only over resistance 5 but also over a rectifier 6, connected in the reverse direction, a resistance 7 and a resistance 8 to ground. The junction point between rectifier 6 and resistance 7 is connected over a resistance 9 to the control electrode of tube 2. The reverse resistance of rectifier 6 is about 20 megohms and the resistances 7 and 8 together are about $\frac{1}{2}$ megohm. The potential drop impressed between control electrode and cathode of tube 2 is therefore only a few volts and is insufficient to cause tube 2 to become conducting even when an impulse is applied to conductor 10, connected to the control electrode of this tube 2.

Suppose now that instead of tube 1, tube 3 becomes conducting. The current in this tube passes through resistances 11 and 8 to ground and also through resistance 7, rectifier 6 and resistance 5 to ground, i. e. through the rectifier 6 in the forward direction.

The resistance of rectifier 6 in the forward di-

rection is about 30,000 ohms, so that resistance 1 is large with respect thereto and the potential at the junction point between resistance 7 and rectifier 6 due to the current rise in the tube 3 only is only a few volts. The fact that tube 3 is conducting is insufficient to cause tube 2 to become conducting when an impulse occurs on conductor 10.

Now consider the case in which both tube 1 and tube 3 are conducting. Neglecting for a moment the connection through rectifier 6 and resistance 7, the junction point between resistances 4 and 5 is at the same potential, =35 volts, as the junction point between resistances 11 and 8. The connection between these two points over rectifier 6 and resistance 7 does not therefore disturb the potential gradient and the junction point between rectifier 6 and resistance 7 is also at 35 volts positive potential and this is impressed upon the control electrode of tube 2.

The effect therefore of both tubes 1 and 3 being conducting is to cause the control gap of tube 2 to be ionised on the arrival of the next impulse on conductor 10.

It can readily be seen that by suitable selection of the values of the fixed resistances and the values of the reverse and forward resistances of the rectifiers it is possible to arrange that the conditions in which the control gap of a final tube becomes ionised on the receipt of an impulse is only obtained when three, four or more preceding tubes have been rendered conducting. The only relevant effect of any tube becoming conducting is that current passes across the anode-cathode path. If the cathode is connected to earth (or the negative terminal of the source of positive potential applied to the anode) through a resistance there will be a potential drop along this resistance and any desired potential can be obtained by tapping a suitable point along this resistance. Thus the junctions between resistances 4 and 5 and between resistances 8 and 11 in Fig. 1 are such tappings.

For the purpose therefore of considering how the circuit should be arranged to make the initiating ionisation of a principal tube dependent on a predetermined number of preceding tubes having become conducting, it is only necessary to consider the potentials at the tapping points referred to above associated with a number of 50 similarly connected tubes such as tubes 1 and 3 in Fig. 1.

In Fig. 2 there is shown diagrammatically an arrangement which represents the relevant conditions in Fig. 1. Thus point 12 can be considered to be the junction between resistances 4 and 5 of Fig. 1, and point 13 corresponds similarly to the junction between resistances 8 and 11. Resistance 16 represents resistance 7 of Fig. 1, and point 14 represents the control electrode of tube 2. Resistance 9 of Fig. 1 is omitted from the equivalent circuit shown in Fig. 2 as it plays no part in the circuit for applying potential derived from points 12 and 13 to point 14 and is only required to limit the current passing over the control gap of tube 2 after ionisation has been set up.

The purpose of this circuit is therefore to impress a potential bias on point 14 (where point 14 is of high resistance to ground), when potential is applied to both points 12 and 13 which points have a relatively low resistance to ground, but not to impress any appreciable potential bias on point 14 when there is no potential applied to either points 12 or 13 or to one only of these

points. The relatively low resistance to ground of points 12 and 13 is represented by resistances 17 and 18 corresponding to the ground connections through resistances 4 and 5 in the case of tube 1 and 8 and 11 in the case of tube 3 as shown in the Fig. 1.

The equivalent circuit of Fig. 2 corresponds with that shown in Fig. 1 but is in fact a special case of a more general circuit which is shown in Fig. 3 and the operation of the circuit of Fig. 2 will be better understood, after the operation of the circuit of Fig. 3 has been explained.

The only difference between Fig. 3 and Fig. 2 is that in Fig. 3 resistance 16 has been replaced by a rectifier 19 having the same characteristics as rectifier 15.

Considering Fig. 3, it is evident that if there is no potential applied to either point 12 or 13 no potential can be developed at point 14. When however a positive potential is applied to point 12 with point 13 remaining at ground potential rectifier 15 is biassed by the potential at point 12 to its backward or high resistance direction, thus causing the circuit to act as a high ratio potential divider from points 12 and 13 to point 14. A small residue potential will appear at point 14 but as this biasses rectifier 19 to its forward or low resistance direction the potential at point 14 is of negligible value.

It is evident of course that exactly the same effect will be obtained if positive potential is applied to point 13 while point 12 is held at ground potential.

When however an equal potential is applied to points 12 and 13 it is evident that this same potential will appear at point 14, which is of high resistance to ground. It can immediately be seen that further points corresponding to 12 and 13 can be connected through rectifiers similar to rectifiers 15 and 19 to the common point 20 and that provided any one of the points 12, 13 or corresponding points is held at ground potential no appreciable potential will be developed at point 14 when the remaining points 12, 13, etc., are raised to a positive potential. There is of course a limit to the number of connections which can be made to point 20 determined by the ratio of the backward resistance of the rectifiers to the forward resistance. If n be the maximum number of rectifiers which can be introduced and R (backward) and R (forward) the resistances of one rectifier then n can be determined from the conditions that

$$\frac{R(\text{backward})}{R(\text{forward})} = n-1$$

must be greater than R (forward).

Taking the values of 20 megohms for R (backward) and 30,000 ohms for R (forward) as quoted by ways of example earlier in this description this indicates that it would theoretically be possible to connect over 600 rectifiers to point 20 before the potential developed at point 14 was equal to that applied at all the points 12, 13, etc., except 1.

However in order to keep the potential at point 14 of negligible value this number of 600 would have to be very considerably reduced and in practice the maximum number of rectifiers which could be connected would be determined by the rise of potential at point 14 which could be tolerated.

Returning now to the circuit shown in Fig. 2 it can be seen that this is only a simplified form of that shown in Fig. 3. Resistance 16 is shown 75 as replacing rectifier 19 and the desirable value

R, of this resistance is given by the expression

$$\frac{R}{R \text{ (backward)} + R} \approx \frac{R \text{ (forward)}}{R \text{ (forward)} + R}$$

Using the values for R (backward) of 20 megohms and for R (forward) of 30,000 ohms as in the example above this gives a value for R of about 8,000,000 ohms. It can be seen therefore that as this value for resistance 16 is high compared with the forward resistance but low compared with the backward resistance of rectifier 15 the circuit of Fig. 2 will behave very similarly to that of Fig. 3 described above.

Fig. 4 shows an embodiment of the invention in which six cold-cathode tubes are connected up so that a principal tube can only be rendered conducting when all the other five tubes are already conducting.

The five tubes 21 to 25 inclusive are shown with positive potential applied to the anodes. The control electrodes represented by arrow heads, are shown on the left in all cases and the tubes can be made conducting by suitable potentials applied to these control electrodes from any source, e. g. potentials desired from the cathode circuits of other similar tubes, impulses from a generator, or potentials from a source such as a battery. The principal tube which is to have potential applied to its control electrode only when the five tubes 21 to 25 are all conducting is tube 26. The cathode of tubes 21 to 25 are connected to ground through resistances 27 to 31 respectively. Rectifiers 32 to 36 are connected between suitable tapping points on resistance 27 to 31 and a common conductor 37. The rectifiers are arranged so that they present their high resistance to positive potentials developed on the cathodes of the tubes with which they are individually associated. The common conductor 37 is connected to the control electrodes of tube 26. When any of the tubes 21 to 25 are conducting the small current which passes through the associated rectifiers does not result in any appreciable potential being developed on the control electrode of tube 26 so long as at least one of the tubes 21 to 25 is not conducting. Assuming for example that tubes 21, 22, 23 and 25 are conducting but tube 24 is not conducting. Then rectifiers 32, 33, 34 and 36 will be biased to their high resistance value and the small currents which pass through these rectifiers will bias rectifier 35 to its low resistance value and pass via part of resistance 30 to ground, so that conductor 37 and the control electrode of tube 26 will be held at a potential not much above ground potential. When however tube 24 becomes conducting in addition to tubes 21, 22, 23 and 25 rectifier 35 becomes biased to its high resistance value and the potential developed at the five tapping points on resistances 27 to 31 appears on the control electrode of tube 26. This potential can be arranged to be sufficiently high to ionise the tube but it is more usually arranged to be rather lower than the ionising potential so that the tube will become conducting on the application of an impulse applied to conductor 38. The actual potential developed in conductors 37 when all five tubes 21 to 25 are conducting is determined for any given case by the selection of the tapping points on resistances 27 to 31.

The arrangements described therefore permit of a principal tube becoming conducting only when a plurality of prerequisite conditions have been fulfilled and have resulted in a plurality of preceding tubes having been made conducting.

While the principles of the invention have been

described above in connections with specific embodiments and particular modifications thereof, it is to be clearly understood that this description is made only by way of example and not as a limitation on the scope of the invention.

What is claimed is:

1. Electric circuit arrangement using gas filled cold cathode electric discharge tubes, each tube having at least a control electrode and a cathode, comprising a principal tube, a pair of similar additional tubes, circuits connecting the cathodes of said additional tubes to ground over individual resistances, an electrical connection from a point on one of said resistances to the control electrode of said principal tube said connection including a rectifier so poled as to offer high resistance to the flow of current to said control electrode, and a connection from a point on said other resistance over a resistance low compared with the backward resistance of said rectifier to a point between the said rectifier and control electrode, the said resistances being so proportioned that a discharge in one only of said additional tubes will not cause the application of a priming potential between control electrode and cathode of said principal tube for initiating a discharge in said principal tube whilst a discharge in both said additional tubes will cause the application of said priming potential between the control electrode and cathode of said principal tube.
2. Electric circuit arrangement using gas-filled cold cathode electric discharge tubes, each tube having at least a control electrode and a cathode, comprising a principal tube, a plurality of similar additional tubes, circuits connecting the cathodes of said additional tubes to ground over individual low resistances, electrical connections from similar points on said resistances to a common point over individual rectifiers, each so poled as to offer high resistance to the flow of current to said common point and an electrical connection between said common point and the control electrode of said principal tube.
3. Electric circuit arrangement comprising a principal tube and a plurality of additional tubes, each of said tubes being gas-filled and having an anode, a control electrode and a cold cathode means for applying potential between control electrode and cathode of said principal tube of insufficient magnitude to initiate a discharge in said principal tube when no further biasing potential is applied to said control electrode, individual connections from the cathodes of each of said additional tubes to ground over low resistance paths, a source of potential insufficient by itself to cause ionisation of the gas in any of said tubes connected to apply positive potential with respect to ground to the anode of each of said tubes, electric connections between points on each of said low resistance paths over individual rectifiers in the backward direction to the control electrode of said principal tube such that if all said additional tubes are conducting a biasing potential is impressed upon the control electrode of said principal tube sufficient together with said first mentioned potential to cause said principal tube to become conducting whereas if any of said additional tubes is non-conducting the potential impressed on the control electrode of said principal tube is too low to be a biasing potential.

ROLAND HARRIS DUNN.
